UNITED STATES PATENT OFFICE.

ADELAIDE STARR HEMSTREET, OF INDIAN HEAD, SASKATCHEWAN, CANADA.

COMBINED CROCHET WORK-BAG AND SPOOL-HOLDER.

1,092,792.

Specification of Letters Patent.

Patented Apr. 7, 1914.

Application filed June 24, 1912. Serial No. 705,651.

To all whom it may concern:

Be it known that I, ADELAIDE STARR HEM-
STREET, a subject of the King of Great Brit-
ain, and resident of Indian Head, Sas-
5 katchewan, Canada, have invented certain
new and useful Improvements in Combined
Crochet Work-Bags and Spool-Holders, of
which the following is a specification.

The invention relates to improvements in
10 combined crochet work-bags and spool-
holders, as described in the present specific-
cation, and illustrated in the accompanying
drawings that form part of the same.

The invention consists essentially of a
15 waist-strap, having a double-armed bracket
secured thereon, and receiving a removable
spool-holding spindle, and a pocket secured
to said waist-strap and extending down-
wardly therefrom beneath said double
20 bracket.

The objects of the invention are to devise
a holder for crochet-work or the like, which
shall facilitate the keeping of the work in
order, will support the thread in constant
25 readiness for use, and will contain the work
complete with crochet-needles or other in-
struments when not in use.

In the drawings, Figure 1 is a perspective
30 view of the invention. Fig. 2 is a plan
sectional view through the spool-holder.
Fig. 3 is an end elevation view of the spool-
holder.

Like numerals of reference indicate corre-
35 sponding parts in each figure.

Referring to the drawings, 1 is a waist-
strap made of any desired material, and
having the buckle 2 at one end thereof.

3 is a pocket comprising the back-piece 4
and the front-piece or pocket proper 5 se-
40 cured thereto. The back-piece 4 of the
pocket is stitched along the waist-strap 1
intermediate of the width thereof and ad-
jacent the buckle 2.

6 is a bracket having the arms 7 and 8
45 extending outwardly from the back-piece 9.
The back-piece 9 is formed with the flaps
10, which are bent over the waist-strap 1
and firmly secure said waist-strap between
50 the back-plate 9 and said flaps 10, whereby
the bracket is supported from said waist-
strap with the arms 7 and 8 projecting out-
wardly. The arms 7 and 8, as also the back-
plate are suitably ribbed at 11 to materi-
55 ally strengthen and add to the rigidity of
the bracket when formed from a light sheet-

metal as shown in the accompanying draw-
ings. The arms 7 and 8 are also formed
with the border flanges 12 for the purpose
of strengthening the same and rendering
them rigid. The arms 7 and 8 at the outer
60 ends thereof have the tabs 13 and 14 respec-
tively, formed from extensions at the end
of the flanges 12, said tabs being turned
back upon the side arms in the direction of
the back-plate 9.

15 and 16 are orifices through the arms 7
and 8 adjacent the outer ends thereof, said
orifices being covered on the outer side by
the tabs 13 and 14.

17 are slots in the arms 7 of the bracket. 70

18 is a flat spring having one end thereof
threaded through the slots 17, whereby it
is securely held in position on the outside
of the arm 7 at the inner end thereof, and
extending inside the tab 13 and covering the 75
orifice 15.

19 is a spindle having a collar 20 formed
adjacent one end thereof.

The spindle 18 may be readily inserted
in the bracket by placing the end with the 80
collar 20 in the orifice 15, and forcing the
same through said orifice against the spring
18, until the opposite end of said spindle
may be inserted in the orifice 16 in the op-
posite arm, the spring 18 moving the spindle 85
into the orifice 16 a sufficient distance to re-
tain the spindle in position for holding a
spool or ball of crochet material.

It must be understood that a plain spindle
may be used, though the collar 20 provides 90
a means for readily placing the spindle in
position, or removing the same when a spool
is used, which takes up almost the entire
length of the spindle. In this case, it would
not be convenient to remove the spindle 95
with the fingers, and it is only necessary to
move the spool along until it contacts with
the collar 20, when the spindle may be
pushed inwardly against the spring to re-
lease the opposite end.

It must be understood that many forms
of bracket, as also many modifications in
the arrangement of the spindle and the
means of securing the same in the bracket
may be made without departing from the 105
spirit of my invention.

The combined spool-holder and pocket
will be found most convenient in doing such
work as crocheting, as the thread or other
material held by the bracket is always in 110

readiness for use, and at any time it is desired the work may be readily placed in the pocket without deranging the same.

What I claim as my invention is:

- 5 1. In a device of the class described, the combination with a waist-strap, of a bracket comprising a base-plate having flaps formed integral therewith and clamped about said waist-strap and a pair of arms extending outwardly therefrom and having orifices toward the outer ends thereof, a spindle extending through the orifices in said arms and spring means for retaining said spindle in said orifices.
- 10 15. 2. In a device of the class described, the combination with a waist-strap, of a bracket formed of sheet metal and having a pair of

flaps clamping about said waist-strap, a pair of side arms having the ends thereof turned back upon themselves and a pair of orifices toward said ends in alignment with said turned-back portions, a flat spring secured to one of said side brackets and extending under the turned-back end thereof and over the orifice and a spindle having a collar formed adjacent one end thereof and fitting the orifices in said arms and bearing against said spring.

Signed at Indian Head, Saskatchewan, this 20th day of February, 1912.

ADELAIDE STARR HEMSTREET.
